**APPARATUS AND METHOD FOR PRODUCING
THIN FILM MATERIALS**

Meyer Piet, Arcadia, Calif., assignor to Futurecraft Corporation, City of Industry, Calif., a corporation of California

Filed June 11, 1962, Ser. No. 201,440

12 Claims. (Cl. 22—67)

The present invention relates generally to the formation of the thin film sheet materials, and is more particularly concerned with apparatus and method whereby a material may be formed into a thin film sheet material having characteristics unlike those of the material in its solid or liquid equilibrium state.

Research in the field of thin films reveals that many materials including certain metallic alloys, when formed into thin films under predetermined ambient conditions, acquire quite different characteristics than the material may have in a normal liquid or solid state. For example, the thin film material may have different mechanical, electrical and magnetic properties that make them particularly adaptable for use in semiconductor technologies.

As a result of investigations in this field, a number of procedures have been suggested for the forming of thin films of materials, but these procedures have in the main been rather complicated, and in some cases have involved techniques which are difficult to control. For these reasons, thin films of acceptable uniformity have been substantially unobtainable. For example, one such procedure involved the projection of molten pellets of material against against the inner surface of a rotating drum which was cooled by liquid nitrogen. Such process has the inherent disadvantage that the pellets may be of variable size, and due to the removal of heat from one side only of the material impinging on the drum, there is a tendency to set up undesirable internal stresses in the film, and the film thicknesses may vary considerably.

Having the foregoing in mind, the present invention proposes to provide a method and apparatus for carrying out the method, wherein the important steps of the method, and the operation of the coating parts of the apparatus are susceptible of precise control and operation, and wherein the ambient operating conditions may be readily established, varied and controlled so as to produce thin films having a high degree of uniformity.

A further object is to provide apparatus for the production of thin films which is of simple construction and operation, and which is suitable for the commercial production of thin films having a high degree of uniformity.

A further object is to provide in such apparatus, unique control means for timing the operation of the hammer and anvil in relation to the release of the molten material.

Another object is to provide apparatus in which the molten material will be dropped and moved by gravity to a position in the path of movement of the hammer to the anvil so as to take advantage of the tendency of the material to naturally form into a globule.

A still further object resides in the provision of a resiliently mounted anvil which prevents the setting up of internal stresses which might disrupt the fragile film.

Still another object is to provide means whereby the globule during deformation into a thin film will be rapidly cooled by conducting heat away from both sides, thus preventing distortion and producing a more homogeneous film material.

Yet another object is to provide an improved method for the production of thin film materials of the character described herein.

In its basic concept, the present invention briefly comprises apparatus which will enable a quantity of the material to be reduced to a molten state and dropped into a

2

space between a latched pre-energized hammer and resiliently mounted anvil. The dropped molten material will tend to form into a globule, and by timing the release of the molten material and the release of the latched hammer, the hammer and anvil will subject the falling globule to a relatively high impacted pressure and deform the material into a thin film.

Simultaneously with the deformation of the globule into a film, the material is rapidly cooled by means of heat conducting surfaces carried by the hammer and anvil, the removal of heat from the opposite sides of the material during the film formation operating to prevent distortion of the film and the setting up of internal stresses therein.

15 The design of the apparatus is such that the hammer and anvil may be readily positioned in a variable environment chamber, or, if desired, the entire apparatus, due to its small size, may be encased in a vacuum chamber or chamber containing a fluid which will provide the desired environment.

Further objects of the invention will be brought out in the following part of the specification, wherein detailed description is for the purpose of fully disclosing the invention without placing limitations thereon.

25 Referring to the accompanying drawings, which are for illustrative purposes only:

FIG. 1 is a perspective view of apparatus for the practice of the method according to the herein described invention;

30 FIG. 2 is a longitudinal horizontal section, taken substantially on the line 2—2 of FIG. 1;

FIG. 3 is an enlarged fragmentary vertical sectional view taken substantially on line 3—3 of FIG. 2, and showing the relationship of the melting chamber in relation to the

35 hammer axis of movement; and

FIG. 4 is a view diagrammatically illustrating the operative relationship of the parts of the apparatus, and schematically showing the timing control therefor.

Referring generally to the drawings, for illustrative purposes, the apparatus for practicing the method of the present invention is shown in FIG. 1 as comprising a high pressure casing 10 which may be constructed in various ways, but in the present instance is disclosed as comprising lower and upper block portions 11a and 11b which are machined or otherwise fabricated to provide a main cylinder 12 in one end portion thereof.

The cylinder 12 is closed at its outermost end by a head bushing 13 which forms a terminal connection for a supply line 14 for pressurized fluid, the fluid being admitted to the cylinder through an inlet bore passage 15. The bottom of the cylinder is closed by an internal wall partition 16 which separates the cylinder interior from a space 17 which is in communication with the casing exterior.

55 A piston 18 having a peripheral seal 19 is mounted for reciprocable movement within the cylinder, this piston having a guide rod 20 which extends through the wall partition 16 and is peripherally sealed by a circumferentially extending sealing ring 21 recessed in the partition wall. Adjacent the partition wall 16 is a second fluid inlet bore 22 which connects with a fluid supply line 23 from which pressurized fluid may be admitted to this side of the piston to force the piston in a direction toward the head bushing 13.

60 65 The outermost end of the guide rod 20, which is positioned within the space 17, is fitted with a cylindrical head member 24 which is formed with a right angled planar end surface 25 within which there is flush seated a disc member 26 of a material having a high heat conduction characteristic, such as copper.

70 75 The right end of the casing 10 is provided with a threaded projecting boss 27 containing a central bore

28 which is coaxial with the head member 24 and guide rod 29. An end cap 29 of generally cupped construction is mounted with its cupped end releasably connected to the boss 27 and retained in operative position by means of a retaining collar 30 having threaded connection with the boss.

The secured end of the cap 29 is internally formed to provide a cylinder 31 within which there is reciprocably mounted an associated piston 32, this piston being sealed at its periphery by a recessed sealing ring 33. The piston is integrally formed intermediate the ends of a tubular member 34, one end as indicated at 35 being positioned within the central bore 28, and the other end 36 being reciprocably supported and sealed by a sealing member 37 within a bore 38 at the outer end of the cap 29. As thus arranged, the piston is axially reciprocable between a shoulder 39 formed on the boss 27 and an internal shoulder 40 formed on the inner wall of the end cap 29. The outer end of the cylinder 31 connects through an annular passage 41 with a supply line 42 for a pressurized fluid which will operate to force the piston 32 in a direction towards the shoulder 39.

The innermost end 35 of the tubular member 34 is formed with a planar end surface 43 within which there is flush seated a disc member 44 of similar construction to the disc member 26. The disc member 44 bears against the adjacent end of an elongate plug member 45 which is removably mounted within the tubular member 34 by means of threaded engagement therewith at its outermost end, a multisided end portion 46 being provided to receive a suitable wrench for removal and insertion of the plug.

As thus far described, it will be observed that the discs 26 and 44 provide in effect cooperably associated working surfaces of a hammer in the case of the head member 24, and a resiliently mounted anvil in the case of the dashpot effect of the piston 32 within the cylinder 31. Moreover, it will be apparent that if suitable means are provided for releasably latching the head member 24 so that the disc 26 is in spaced relation to the disc 44, the piston 18 may be pre-energized by the admission of high pressure fluid from the supply line 14 into the cylinder, and that when the latching means are released, the head member will be impelled so as to carry the disc 26 in a direction to engage the disc 44 with an extremely high impacted force which will be resiliently received due to the dashpot effect of the piston 32 in the cylinder 31.

As shown in FIG. 2 the latching means in this case comprises a latch member 47 which is reciprocably mounted adjacent the wall partition 16 with one end extending into the space 17, this end being provided with a projection 48 arranged to engage behind a peripheral radial shoulder 49 on the head member 24, when the head member is moved to its latching position.

The outermost end of the latch member 47 is provided with an end portion 50 which forms a piston having operative relation with a cylinder bore 51 which is closed by an end cap 52. The latch member 47 is normally urged towards a latching position by means of a compression spring 53 having one end mounted within a socket of the latch member at its opposite end positioned within a socket in the end cap 52. Bevelled surfaces 54 and 55 permit movement of the head member 24 past the projection 48 into a latched position. Unlatching of the latch member is accomplished by subjecting the inner side of the piston 50 to fluid pressure through a connecting bore passage 56 having communication with a supply line 57.

Referring to FIG. 3, the mechanism is disclosed for melting and releasing the molten material for movement to a position between the hammer and anvil for deformation into a thin film. As shown, a pair of members 58 and 59 are supported in end-to-end relation in axial alignment, these members being provided with cooperative end cavities which will form a small chamber 60 that is positioned above the path of travel of the hammer head mem-

ber 24. The members which form this cavity are constructed of carbon or other material which will stand relatively high temperatures, and which will enable melting of the material placed within the chamber 60. Release of the molten material from the chamber may be accomplished in a number of ways, one of which as disclosed comprises the mounting of one of the members in a supporting block 61 so as to be permanently positioned, while the other member, in this case member 58 is supported for relative axial movement into opened and closed position with respect to the fixed member 59. Various means may be utilized for melting the material within the chamber 60. A gas jet may be used for such purpose, or as subsequently explained the material may be reduced by inductive heating.

The member 58 as its outermost end is axially mounted on a cylindrical member 62 which is supported for reciprocable movement within the bore 63 of elongate guide member 64, the guide member being secured at one end to the top of the casing 10 by means of a retaining clamp 65 held in place by securing bolt 66-66. The cylindrical member 62 is urged in an outward direction by means of a compression spring 66 surrounding the member 58 and having one end bearing against the cylindrical member and its other end bearing against an end wall 67 of the clamp, the member 58 extending through an opening 68 therein. The cylindrical member may be latched in a position in which the ends of the members 58 and 59 are engaged to form the chamber 60, the spring 66 in the latched position being under compression. In latched position, a removable latch pin 69 extends into a circumferentially extending groove 70 of the cylindrical member. It will be apparent that lifting of the latch pin 69, so that its inner end is removed from the groove 70, will permit the actuation of member 58 to a separated position with respect to member 59 under the action of spring 66. Separation of these members will permit the melted material in chamber 60 to fall into the space between the hammer and anvil, when the hammer is in latched position. During this falling movement, there is a natural tendency of the molten material to form into a globule.

A stop pin as shown at 70 or other suitable means may be provided to limit the movement of the cylindrical member 62 under the action of the spring 66, and keep this member from being ejected from the bore 63. The cylindrical member may be returned to a latching position by means of a rod or elongate member inserted within the open end of the bore 63. While the latch pin 69 has been disclosed in the present instance as being manually removable, provision may be provided for moving the pin by means of a solenoid or other mechanical means, if desired.

As further shown in FIG. 3, the outermost end of the cylindrical member 62 is provided with a beveled edge 71 which provides a camming action to motivate an actuating pin 72 of a micro-switch 73 carried by an adjustable clamp bracket 74 which may be secured in a desired adjustable position on the guide member 64 by means of a screw 75. The top surface of the guide member is provided with an elongate slot 76 through which the pin 72 projects into the bore 63, thus permitting adjustable variation of the position of the micro-switch 73 and the consequent timed relation of its actuation with respect to release of the melted material from the chamber 60. Actuation of the micro-switch will be utilized to trigger further operations as will now be explained by reference to FIG. 4.

As shown in FIG. 4, it is proposed to inductively melt the material in the chamber 60 by means of an electrically energizable coil 77, the cylindrical member 62 being retained in latched position by the latching pin 69. At this time, the latch member 47 will be in latching position retaining the head member 24 in the position shown in FIG. 2. In this position, the piston will be pre-energized by admitting fluid under relatively high pressure through the

inlet bore 15. Such fluid pressure may be of the order of several hundred pounds. To release the molten material, the latch pin 69 will be withdrawn to permit separation of the members 58 and 59, whereupon the material will fall by gravity and form into a globule as indicated by the numeral 78.

The latch 47 is released in proper timed relation to permit movement of the hammer head member 24 in cooperation with the anvil to catch the globule while therebetween and deform it into a thin film. The timing is controlled by the adjustable setting of the micro-switch 73 on the guide member. The cylindrical member operates to close the contacts of the micro-switch and establish an electrical circuit through conductors 79 and 80 to a solenoid actuated valve 81 which opens upon energization to supply pressurized fluid through line 57 and thus release the latch 47. This permits movement of the pre-energized hammer head 24 in cooperation with the anvil member to apply high impact pressure to the globule and deform it into a thin film. During this deformation, the resiliency or dashpot effect of the anvil prevents the setting up of internal stresses within the film or its disruption due to its fragile nature. Moreover, at the same time the film is being deformed, it will be quenched by abstracting heat from its opposite sides, thus producing a more homogeneous structure.

While the space 17 is shown as being open in the present instance to atmosphere, it is conceivable that the space surrounding the hammer and anvil and the members 58 and 59 may be closed to provide desired environmental control. On the other hand, the apparatus of the present invention is physically of small size which would permit its being placed in its entirely within a vacuum chamber or other controlled chamber to provide environmental control.

While the device and method as described may be operated at room temperatures, cooling procedures may be readily applied, if necessary.

Various modifications may suggest themselves to those skilled in the art without departing from the spirit of my invention, and, hence, I do not wish to be restricted to the specific form shown or uses mentioned, except to the extent indicated in the appended claims.

I claim:

1. Apparatus for producing thin films of sheet-like material, comprising:

- (A) anvil means;
- (B) hammer means supported for movements between a spaced position and engaged position with respect to said anvil means;
- (C) means for latching said hammer means in said spaced position;
- (D) means for energizing the latched hammer means;
- (E) means for introducing a quantity of material while in a molten state into a non-contacting position in the space between said hammer means and anvil means, whereby upon release of the latching means, the molten material will be deformed between the hammer means and anvil means into a thin film; and
- (F) elements carried by the anvil means and hammer means for rapidly conducting heat from the material during deformation thereof.

2. Apparatus for producing thin films of sheet-like material comprising:

- (A) an anvil member;
- (B) means including a hammer member supported for movements between a spaced position and engaged position with respect to said anvil member;
- (C) means for latching said hammer member in said spaced position;
- (D) means for energizing the latched hammer member for movement in one direction;
- (E) means for directing a quantity of material while in a molten state into a path of movement travers-

ing the space between said hammer member and said anvil member, whereby upon release of the latching means, the molten material will be engaged and deformed by said members into a thin film; and

(F) means carried by at least one of said members for engaging the material during deformation, said means having a relatively high thermal conductivity, whereby heat energy is rapidly removed from the molten liquid material during the deformation.

3. Apparatus for producing thin films of sheet-like material, comprising:

- (A) anvil means;
- (B) hammer means supported for movements between a spaced position and engaged position with respect to said anvil means;
- (C) means for latching said hammer means in said spaced position;
- (D) means for energizing the latched hammer means;
- (E) means for introducing a quantity of material while in a molten state into the space between said hammer means and anvil means and out of contact therewith, whereby upon release of the latching means, the molten material will be engaged and rapidly deformed between the hammer means and anvil means into a thin film; and
- (F) elements carried by said hammer member and said anvil member for surface engagement with the material, said elements having a relatively high thermal conductivity, whereby heat energy is rapidly removed from opposite sides of the material during the deformation.

4. Apparatus for producing thin sheet-like films of material, comprising:

- (A) an anvil member;
- (B) a hammer member supported for horizontal axial movements between spaced and engaged positions with respect to said anvil member;
- (C) means for releasably latching said hammer member in said spaced position;
- (D) means for energizing the latched hammer member for movement in a direction towards said member;
- (E) means positioned above the space between said hammer member and said anvil member for reducing a quantity of said material to a molten state;
- (F) means for releasing the molten material for movement under the force of gravity into said space; and
- (G) means for releasing said latching means in such timed relation to the release of said molten material that the released material will be intercepted during its movement in said space and deformed into a thin film by the impact of said hammer on said anvil member.

5. Apparatus for producing thin films of sheet material, comprising:

- (A) an anvil member;
- (B) a hammer member supported for horizontal movements between spaced and engaged positions with respect to said anvil member;
- (C) means for releasably latching said hammer member in said spaced position;
- (D) means for energizing the latched hammer member for movement in a direction towards said anvil member;
- (E) means defining a melting chamber positioned above the space between said hammer member and said anvil member, including an element operable to a position in which a globule of molten liquid is released with respect to the chamber for movement under the force of gravity into said space; and
- (F) means for moving said element and releasing said latching means in timed relation, whereby said released liquid globule in said space will be engaged and deformed by said hammer member and anvil member into a thin film.

6. Apparatus for producing thin films of metallic-like sheet material, comprising:
- (A) an anvil member;
  - (B) a hammer member supported for movements between spaced and engaged positions with respect to said anvil member;
  - (C) means for releasably latching said hammer member in said spaced position;
  - (D) means for energizing the latched hammer member for movement in a direction to engage said anvil member;
  - (E) a pair of members supported for relative movement into closed and opened positions, said members in closed position defining a melting chamber, and in opened position enabling movement of melted material under the force of gravity from the melting chamber into the space between said hammer member and said anvil member;
  - (F) means for melting the material in said chamber; and
  - (G) means for actuating said pair of members to opened position, and releasing said latching means in timed relation, whereby melted material will move into said space and be engaged and deformed by said hammer member and anvil member into a thin film.

7. Apparatus for producing thin films of sheet material, comprising:

- (A) an anvil member;
- (B) a hammer member supported for horizontal axial movements between spaced and engaged positions with respect to said anvil member;
- (C) means for releasably latching said hammer member in said spaced position;
- (D) means for energizing the latched hammer member for movement in a direction towards said anvil member;
- (E) means positioned above the space between said hammer member and said anvil member including a chamber for reducing a quantity of said material to a molten state;
- (F) means for inductively melting the material in said chamber; and
- (G) means for releasing molten material from said chamber and said latching means in such timed relation that the released molten material will be intercepted in said space and deformed into a thin film by the impact of said hammer on said anvil member.

8. The method of forming thin films of sheet material, which comprises the steps of:

- (A) forming a globule of molten liquid material;

- 8
- (B) subjecting said globule to an impact pressure to form a film thereof; and
  - (C) rapidly cooling the material during the formation of the film.

9. The method of forming thin films of sheet material, which comprises the steps of:

- (A) forming a globule of molten liquid material;
- (B) moving the globule to a position between separated parallel surfaces;
- (C) moving said surfaces into impact engagement so as to form the globule into a thin film; and
- (D) rapidly conducting heat away from said surfaces to cool the material during the formation of the film.

10. The method of forming thin films of sheet material, which comprises the steps of:

- (A) forming a globule of molten liquid material;
- (B) moving the globule to a position between separated parallel surfaces;
- (C) moving said surfaces into impact engagement so as to form the globule into a thin film; and
- (D) rapidly conducting heat from the opposite sides of the material through said surfaces during the formation of the film.

11. The method of forming thin films of metallic sheet material, which comprises the steps of:

- (A) forming a molten globule of said material;
- (B) subjecting the globule to an impact blow between parallel surfaces to form the globule into a film;
- (C) resiliently absorbing the impact of said blow; and
- (D) quickly cooling the material during the formation of the film by conducting heat away from said surfaces.

12. The method of forming thin films of sheet material, which comprises the steps of:

- (A) melting the material to form a molten mass;
- (B) dropping the molten mass under the action of gravity to form the mass into a globule; and
- (C) subjecting said globule to an impact pressure between parallel surfaces of a high heat conductive material to form a film thereof, and quickly cooling the material during the formation of the film.
